Primary Examiner — John R Yeh(74) *Attorney, Agent, or Firm* — Hsuanyeh Law Group
PC(57) **CLAIM**

The ornamental design for a crystal grid, as shown and described.

DESCRIPTION

FIG. 1 is a front elevation view of our design for a crystal grid.

FIG. 2 is a rear elevation view of the crystal grid as shown in FIG. 1.

FIG. 3 is a right-side elevation view of the crystal grid as shown in FIG. 1.

FIG. 4 is a left-side elevation view of the crystal grid as shown in FIG. 1.

FIG. 5 is a top plan view of the crystal grid as shown in FIG. 1; and,

FIG. 6 is a bottom plan view of the crystal grid as shown in FIG. 1.

The dotted lines in the drawings depict portions of the crystal grid that form no part of the claimed design. The dashed lines around the edges of the crystal grid show stitching and is part of the claimed design.
